FOOD MIXER

Robert O. Ernest, Oak Park, Ill., assignor to Sunbeam Corporation, Chicago, Ill., a corporation of Illinois

Application October 12, 1953, Serial No. 27,133

Term of patent 14 years

(Cl. D44—1)

Fig. 1

Fig. 2

Fig. 3Fig. 4Fig. 5*To all whom it may concern:*

Be it known that I, Robert O. Ernest, a resident of Oak Park, State of Illinois, have invented a new, original, and ornamental Design for Food Mixer, of which the following is a specification, reference being had to the accompanying drawings, forming a part hereof.

Fig. 1 is a perspective view of a food mixer embodying my new design;

Fig. 2 is a side elevational view;

Fig. 3 is a top plan view;

Fig. 4 is a front elevational view; and

Fig. 5 is a rear elevational view.

The essential features of the design reside in the portions shown in full lines.

I claim:

The ornamental design for a food mixer, as shown and described.
